(57) **CLAIM**

I claim the ornamental design for a motorcycle horn cover, as
shown and described.

DESCRIPTION

FIG. 1 is a perspective view of a motorcycle horn cover
showing my new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof; and,

FIG. 7 is a left side elevation view thereof.

The broken lines are for illustrative purposes only and form
no part of the claimed design.
